COIN WRAPPER

Clement Lee Downey, Cincinnati, Ohio

Application November 21, 1938, Serial No. 241,589

4 Claims. (Cl. 229—87)

This invention relates to a coin wrapper of the cartridge or gun-shell type.

An object of the invention is to provide an improved coin wrapper of the character stated, which is so constructed as to be capable of high-speed coin reception from a rapid counting machine.

Another object is to produce a tighter and therefore safer wrapper than has been produced heretofore.

A further object of the invention is to provide a coin wrapper of the character referred to, which may be manufactured inexpensively without scrap and waste of material, while embodying the advantages above stated.

Another object is to provide an improved coin wrapper of the cartridge or gun-shell type, which is so constructed as to eliminate all interference with coin movement into the wrapper, and the jamming of coins incident thereto.

These and other objects are attained by the means described herein and disclosed in the accompanying drawing, in which:

Fig. 1 is a perspective view of a completed coin wrapper of the invention.

Fig. 2 is a plan view of the blank from which the coin wrapper of Fig. 1 is formed.

Fig. 3 is an enlarged diagram showing, in skeleton form, the convolutions of the wrapper and the relationship thereof one to another, the convolutions being shown abnormally separated in the interest of clarity.

The improved coin wrapper is made of a single blank or sheet 5 of paper or similar material, cut and folded as indicated. The drawing is practically to scale, and illustrates a nickel wrapper. It should be noted that the blank has two substantially parallel side edges 6 and 7, and opposed ends 8 and 9. The end 8 is oblique to the side edges, and may be disposed at an angle to the side edge 7, approximately 60 degrees. This angularity, of course, may be altered or modified without departing from the invention.

The end 9 comprises a straight edge, before it is folded over to form the flap 10, and said straight edge preferably, though not necessarily, is parallel to the opposite edge or end 8. By making these ends 8 and 9 parallel, blanks 5 may be cut from suitable sheet material continuously or simultaneously, without waste and scrap to be handled and disposed of.

At a point such as 12, which is about midway between the ends of edge 9, the blank is folded over upon itself, so as to form the triangular tab or flap 10 whose apices are indicated by the char-

acters 12, 13 and 14. The hinge or crease 15 thereby formed is not a raw cut edge like the various edges 6, 7, 8 and 9, and accordingly, it is comparatively free of extending fibers and the minute saw-tooth formations which invariably characterize raw cut edges in paper stock. Moreover, the fold or hinge at 15 provides a reinforcement of a portion of one end of the blank, and it more or less resiliently supports the flap, for purposes to be hereinafter explained.

It should be observed that the end 8 is outside of the wrapper, and the end 9 is inside it, the completed wrapper being formed by merely rolling the blank of Fig. 2 from the bottom upwardly, to produce the cylindrical formation of Fig. 1. The inner end 9—15 is substantially spear-shaped, preferably, and the raw cut edge of end 9 is at an obtuse angle to the smooth or hinge edge 15. The apex 14 of the flap points toward the far end 8 of the blank.

Now, when the wrapper is formed by rolling the blank from the bottom upwardly toward end 8, the fold, crease, or hinge 15 is bent to arcuate formation, so that 15, instead of being straight, becomes slightly curved between the points 12 and 13. The curvature, being in opposition to the tendency of the edge or hinge 15 to maintain a straight line status, imparts a strain and therefore a resiliency thereto, such as will, in the completed cylindrical wrapper, tend to maintain a close contact between the various convolutions of the wrapper. In other words, it becomes a force opposing collapse of the inner convolution toward the center of the cylinder. The closeness of the adjacent convolutions is not indicated in Fig. 3, because that view is merely a diagram intended to show only the number of convolutions and their relationship in general.

The folded or creased edge 15 has a second function, which is that of eliminating any rough or minutely saw-toothed edge such as always characterizes a raw cut in paper. In this connection, it should be understood that the mouth of a coin wrapper must offer no resistance to the entry of coins from the coin counting machine, for the machine delivers coins to the wrapper at a rate of approximately 2000 per minute. Any tendency for the innermost convolution of the wrapper to collapse inwardly of the wrapper, or to unwind, therefore, will obstruct the flow of coins into the wrapper, and will thereby result in a jam or stoppage interfering with continued operation of the counting machine. A rough or saw-toothed edge on the innermost wrapper convolution is capable of starting such a jam or stoppage, due to the fi-

bers of the raw edge intercepting the coins and tending to draw the raw edge down into the wrapper along with the coins as they move toward the rolled edge 16.

5 The mouth of the wrapper is indicated at 17, which is the port at which the coins enter the completed wrapper. The end of the wrapper opposite the mouth 17 is closed, or partly closed, in any suitable manner, such as by upsetting the 10 edge 7 of the blank after it has been rolled to cylindrical form, thereby to form the roll edge 16. Gun-shells of paper are similarly constructed, as is well known, to retain the slug and the charge behind it.

15 The result of the herein disclosed construction, is a coin wrapper of unusual firmness and rigidity, and one which will have no tendency to collapse and offer resistance or obstruction to a high-speed flow of coins thereto from the counting machine. Accordingly, the filling of the device with 20 coins is highly certain and continuous, thereby effecting a saving of time and labor in the production of coin-filled packages. The counting machine rarely jams the coins at the wrapper, when 25 the wrapper is properly constructed in accordance with the teaching herein, thereby obviating much annoyance and delay in the filling of the wrapper with coins. Because the present construction results in what is called a tight wrap, the liability of 30 the filled package to accidental breakage is reduced to a minimum. Since in dieing out the blanks, the end cuts 8 and 9 are parallel, no scrap is produced and all portions of the original sheet 35 are endowed with a useful function or purpose in the completed wrapper.

What is claimed is:

1. A coin wrapper which comprises an elongated sheet of material rolled to cylindrical formation with one end of the sheet disposed without, and the opposite end of the sheet disposed 40 helically within, the cylindrical formation, said helically disposed end being folded upon itself to present a smooth creased edge interiorly of the cylindrical formation, which offers a minimum of 45 resistance to delivery of coins into the cylindrical wrapper, the flap resulting from the fold being disposed between adjacent inner convolutions of the cylindrically wound sheet.

2. A coin package which comprises a series of 50 coins in face to face contact with their edges collectively aligned to form a cylindrical solid body, and a wrapper wound repeatedly about the cylindrical body of coins, said wrapper comprising an elongated sheet of paper-like material having 55 opposite sides and inner and outer ends, the inner end having a corner folded upon itself to

form a flap and a smooth creased edge, the latter being oblique to the major axis of the elongated sheet, and said flap being turned flatwise upon the wrapper to expose the resultant helically creased edge to the edges of the coins in the cylindrical condition of the wrapper while all other edges of the flap rest between the innermost convolutions of the wound wrapper, as and for the purposes described.

3. A coin package which comprises a series of 10 coins in face to face contact with their edges collectively aligned to form a cylindrical solid body, and a wrapper wound repeatedly about the cylindrical body of coins, said wrapper comprising an elongated sheet of paper-like material 15 having inner and outer ends, and opposite side edges defining the mouth of the package and the opposed base thereof, the corner formed by the inner end of the wrapper meeting that side edge which defines the package mouth, being turned 20 upon itself to form a smooth creased edge and a flap, said creased edge extending helically and thereby being arcuately strained throughout its entire length, from the mouth of the package 25 toward the package base, and in contact with only the edges of coins from the mouth inwardly, the flap lying flatwise upon that face of the wrapper which forms an intermediate convolution of the wound wrapper, whereby all edges of the flap, excepting the creased edge, are disposed between 30 the wrapper convolutions and out of contact with the coin edges.

4. A coin package which comprises a series of 35 coins in face to face contact with their edges collectively aligned to form a cylindrical solid body, and a wrapper wound repeatedly about the cylindrical body of coins, said wrapper comprising an elongated sheet of paper-like material having inner and outer ends, and opposite side edges defining the mouth of the package and the opposed base thereof, the corner formed by the inner end of the wrapper meeting that side edge which defines the package mouth, being turned 40 upon itself to form a flap with a smooth creased edge disposed obliquely to the major axis of the elongated wrapper, said creased edge extending from the mouth of the package helically toward the package base, in contact with only the edges of coins from the mouth inwardly, the flap lying 45 flatwise upon that face of the wrapper which forms an intermediate convolution of the wound wrapper, whereby all edges of the flap, excepting the creased edge, are disposed between the wrapper convolutions and out of contact with the coin edges.

CLEMENT LEE DOWNEY.
